PLATE 1
No. 84
10-3-1846

W. & FURN. & FURN.
LIVERPOOL.

P. A. Gregory Design.
Patented Oct. 3rd 1846.

DES.

Fig. 1. & 2. Perspective view.

A. Is the base of the stove.

B. The main cylinder.

C. Side flues, for conveying the gas into the cylinders D. D. when the cylinder B. in the main cylinder is turned, so as to shut off the direct communication with the flue.

D. Side cylinders connected with the main cylinder as shown at A. A. at the base, and the top, by the pipes E. E.

E. E. Connecting pipe from the side cylinders to the main cylinder pipes.

F. F. F. Dampers in the neck of the main side cylinders to regulate the direction of the gas to from the fire.

G. Grate.

H. Air perspective draft holes to admit a current of air under the grate.

I. Anti-puff.

K. Pipe.

L. Pipe to the pipe.

Des. 86

Robert A. Gregory, New York,
Letters Patent (designate 86) dated 8th October 1846

The schedule referred to in these Letters Patent annexing
part of the same

To all whom it may concern:

Be it known,

that I, Robert A. Gregory of the City, County and State of New York, have invented or produced a new design or pattern of a Parlor Stove which I have called the "Knickerbocker Stove" and I do hereby declare that the following is a full and exact description of the same.

The nature of my invention consists in the combination of three cylinders, connected at the base and top to the main cylinder by arms or flues so as to communicate the current of flame and gas to the outer cylinders when the damper is turned off in the main cylinder, on the cylinders are arranged three conical caps (something like the mouth of a flue) one over the other, the base of the caps standing over the neck of the one underneath so as to give an ornamental appearance to the stove, while at the same time giving a greater amount of radiating surface than could be obtained by any other arrangement of cylinders - on the base of each of these caps are also attached an ornamental border of bronze, so that when the stove is complete a most harmonious effect is produced upon the mind of the sitter in a room. But to describe the stove more particularly reference will be made to the accompanying drawings. Figs 1&2 are sectional perspective views, Letter A represents the base - B the main cylinder - C.C. sectional view - side flues for conveying the flame and gas into the cylinders D.D. when the damper E in the main cylinder is turned so as to shut off the direct communication with the smoke pipe K. - D.D. side cylinders connected with the main cylinder as shown at letter A, and at the top by the pipes E.E. - B, B, connecting pipes from the side cylinders to the main cylinder.

Dec. 86

pipe - F.F.E. dampers in the necks of the main and side cylinders to regulate the direction of the flame and gas from the fire. At the grates, arranged in the same manner as in the ordinary cylinder stove.

H. perspective view draft holes to admit a current of air underneath the fire, I. the ash pan - K small pipe attached to the top of the main cylinder & the ornamental borders to the base of the several caps to each cylinder.

In the perspective view will be seen the general design or pattern of the stove - the outer cylinders or columns having somewhat the appearance of columns surmounted by capitals, and the main cylinder similarly ornamented completing the whole arrangement so as to give the most profanity to design.

Now what I claim and wish to secure by Letters patent is, the design or pattern of the three cylinders with the arrangement of the caps and borders so as to give the appearance, in some respects, of a combination of Corinthian Columns with their capitals, and the particular form of the pattern as described and represented in the perspective drawing accompanying this description and claim.
